(57) **CLAIM**

The ornamental design for a cat tree, as shown and described.

DESCRIPTION

FIG. 1 is a top, front, right perspective view of a cat tree showing our new design;

FIG. 2 is a bottom, back, left perspective view of the cat tree;

FIG. 3 is a front elevational view of the cat tree;

FIG. 4 is a rear elevational view of the cat tree;

FIG. 5 is a left side elevational view of the cat tree;

FIG. 6 is a right side elevational view of the cat tree;

FIG. 7 is a top plan view of the cat tree;

FIG. 8 is a bottom plan view of the cat tree;

FIG. 9 is an enlarged view of part 9 in FIG. 1; and,

FIG. 10 is an enlarged view of part 10 in FIG. 1.

The dash-dot broken lines in FIGS. 1, 9 and 10 are for the purpose of illustrating the boundaries of the enlarged fragment views shown in FIGS. 9 and 10, and form no part of the claimed design. The dotted broken lines in the drawings are for the purpose of illustrating portions of the article that form no part of the claimed design.

1 Claim, 10 Drawing Sheets
